UNITED STATES PATENT OFFICE

160,157

KEY

Raymond H. Foor, Los Angeles, Calif.

Application July 22, 1949, Serial No. 4,079

Term of patent 3½ years

(Cl. D50—4)

To all whom it may concern:

Be it known that I, Raymond H. Foor, a citizen of the United States of America, residing in the city of Los Angeles, in the county of Los Angeles, State of California, have invented a new, original, and ornamental Design for a Key, of which the following is a specification, reference being had to the accompanying drawing, forming a part thereof.

Figure 1 is an elevational view of a key, embodying my new design;

Figure 2 is a top plan view of the same;

Figure 3 is a view from one edge, a portion of the key being omitted for convenience in illustration;

Figure 4 is a sectional view, taken at 4—4 in Figure 1; and

Figure 5 is a sectional view, taken at 5—5 in Figure 1.

The characteristic features of my design reside in the portions shown in full lines.

I claim:

The ornamental design for a key, substantially as shown and described.

RAYMOND H. FOOR.
